US0D1060261S

(12) **United States Design Patent** (10) **Patent No.:** **US D1,060,261 S**
(45) **Date of Patent:** **** Feb. 4, 2025**

(54) **ADAPTER FOR ELECTRICAL CONNECTOR SOCKETS**

(71) Applicant: **GONEO GROUP CO., LTD.**, Ningbo (CN)

(72) Inventors: **Jianmin Zhou**, Cixi (CN); **Qihao Ma**, Cixi (CN); **Baichuan Huang**, Cixi (CN); **Shibo Gao**, Cixi (CN)

(**) Term: **15 Years**

(21) Appl. No.: **35/519,070**

(22) Filed: **Sep. 20, 2023**

(80) **Hague Agreement Data**

Int. Filing Date: **Sep. 20, 2023**

Int. Reg. No.: **DM/233087**

Int. Reg. Date: **Sep. 20, 2023**

Int. Reg. Pub. Date: **Nov. 17, 2023**

(30) **Foreign Application Priority Data**

Mar. 21, 2023 (CN) 202330136543.6

(51) **LOC (15) Cl.** **13-03**

(52) **U.S. Cl.**

USPC **D13/137.2**

(57) **CLAIM**

The ornamental design for an adapter for electrical connector sockets as shown and described.

DESCRIPTION

2.1 : Front view of an adapter for electrical connector sockets showing our new design;

2.2 : Back view of the adapter;

2.3 : Left view of the adapter;

2.4 : Right view of the adapter;

2.5 : Top view of the adapter;

2.6 : Bottom view of the adapter;

2.7 : Front, left side perspective view of the adapter; and

2.8 : Back, right side perspective view of the adapter.

The broken lines in the representations form no part of the claimed design.

1 Claim, 8 Drawing Sheets
